DESIGN FOR A PORTABLE CRANE

Roy H. Zeilman, Lorain, Ohio, assignor to Thew Shovel Company, Lorain, Ohio, a corporation of Ohio

Application May 21, 1942, Serial No. 106,968

Term of patent 14 years

To all whom it may concern:

Be it known, that I, Roy H. Zeilman, a citizen of the United States, residing at Lorain, in the county of Lorain and State of Ohio, have invented a new, original, and ornamental Design for a Portable Crane, of which the following is a specification, reference being had to the accompanying drawings, forming a part thereof, in which:

Fig. 1 is a front perspective view of a portable
crane showing my new design;

Fig. 2 is a rear perspective view;
Fig. 3 is a side elevational view; and
Fig. 4 is a front elevational view thereof.

I claim:
The ornamental design for a portable crane,
substantially as shown.

ROY H. ZEILMAN.
